DESIGN FOR A SOCK

Walter F. Connor and Mary E. Carney, Lowell,
Mass., assignors to Hub Hosiery Mills, Lowell,
Mass., a corporation of Massachusetts

Application October 25, 1937, Serial No. 72,413

Term of patent 14 years

To all whom it may concern:

Be it known that we, Walter F. Connor and Mary E. Carney, citizens of the United States of America, residing at 461 High Street and 19 Mount Vernon Street, respectively, in the city of Lowell, county of Middlesex, and Commonwealth of Massachusetts, have invented a new, original, and ornamental Design for a Sock, of which the following is a specification, reference being had to the accompanying drawing, forming a part thereof.

Fig. 1 is a perspective of a sock embodying our new design displayed as it would appear upon the foot and leg of a wearer; and

Fig. 2 is a side elevation of the sock shown in Fig. 1.

The design comprises an anklet sock having a V-opening in the upper front edge of the ankle portion thereof.

We claim:

The ornamental design for a sock, substantially as shown and described.

WALTER F. CONNOR.
MARY E. CARNEY.
